APPARATUS FOR DRYING WARPS OF
TEXTILES

Ernest A. Stienen, New York, N. Y.

Application June 24, 1937, Serial No. 150,097

1 Claim. (Cl. 34—48)

This invention relates to apparatus for drying warps of textiles.

One of the objects of the invention relates to apparatus for drying warps of textiles to be sized.

A second object of the invention relates to the apparatus for sizing warps of textiles and avoiding injury to them with kinks during their treatment.

The third object of the invention is the production of a drying apparatus for warps of textiles having a drying chamber, through which the warps are moved through circulating heated air, the movement of the warps and the circulation of the air being simultaneously controlled, to cease circulating the air when the warps are at rest to avoid overheating the warps.

The fourth object of the invention is the production of apparatus for drying a warp of textile, impregnated with a sizing fluid to be sized, by circulating heated air against the warp while the latter is moving, and controlling the velocity and volume of said heated air.

In the accompanying drawing Fig. 1 represents an elevation partly in vertical section of the drying apparatus; Fig. 2 shows a top view of Fig. 1; Fig. 3 indicates an enlarged plan view of a detail; Fig. 4 represents an enlarged vertical section of a portion of a detail and Fig. 5 shows a wiring diagram for the electric motors of the apparatus.

The apparatus in this instance comprises a housing, having the front wall 20, the rear wall 21, the top wall 22, and the end walls 23 and 24. Vertically disposed angle irons 25 are provided for the corners of the housing for strength. A horizontal platform 26 divides the housing to provide the heating chamber 27 at the bottom, and the drying chamber 28 above the latter. The floor for the housing is shown at 29.

In the platform 26 is indicated the opening 30 and in the top wall 22 are shown the openings 31 and 32. In the end wall 23 is indicated the opening 33, and in the end wall 24 are shown the openings 34 and 35. Extensions 36 and 37 are provided for the rear wall 21 and extensions 38 and 39 are provided for the front wall 20.

In the drying chamber 28 are shown a plurality of skeleton supporting and conveying drums, respectively indicated in their entirieties by the numerals 41, 42, 43, 44, 45, 46 and 47. In the axial center of each drum is shown a shaft 50, the ends of which are supported in suitable journal bearings, not shown, in the walls 20 and 21. End discs 51 are provided for the drums and are loosely supported on the shafts 50. A plurality of longitudinal supporting bars, 53 spaced from one another and each having an outer curved bearing surface 54, connect the discs 51 of each drum. A rotating fan is shown in each of the drums, and consists of two sets of arms 55, 60 four in number, which extend from the shaft 50

adjacent to the ends of the drum. Longitudinal blades 56 have their ends connected to corresponding arms 55 of each set. A pulley 60 is fastened to the shaft 50 of the drum 42 and a pulley 61 is fastened to the shaft 60 of the drum 41. A belt 62 connects the pulleys 60 and 61. A second pulley 63 is fastened to the shaft of the drum 41. A pulley 64 is fastened to the shaft 50 of the drum 45, and a belt 65 connects the pulleys 63 and 64. A second pulley 66 is fastened to the shaft 50 of the drum 45. A pulley 67 is fastened to the shaft 50 of the drum 47 and a belt 68 connects the pulleys 66 and 67. On the shaft 50 of the drum 43 is fastened the pulley 72 and on the shaft 50 of the drum 44 is fastened the pulley 15 13 and a belt 75 connects the pulleys 72 and 73. To the shaft 50 of the drum 44 is fastened a second pulley 76. To the shaft 50 of the drum 46 is fastened the pulley 77, and a belt 78 connects the pulleys 76 and 77.

Hangers 80 extend from a support 81 and a shaft 85 is journaled in the hangers 80. A pulley 86 is fastened to the shaft 85.

An exhaust fan 90 is fastened to the top wall 22 of the housing over its opening 31. The exhaust fan 90 is shown with its inlet conduit 91 and its outlet conduit 92. The shaft of the exhaust fan is indicated at 93 and has fastened thereto the pulley 94. A belt 95 connects the pulleys 86 and 94. A second pulley 96 is fastened to the shaft 85 and a second pulley 97 is fastened to the shaft 50 of the drum 47 and a belt 98 connects the pulleys 96 and 97. A third pulley 99 is fastened to the shaft 85 and a second pulley 100 is fastened to the shaft 50 of the drum 46. A belt 101 connects the pulleys 99 and 100.

An electric motor 105 is supported on the floor 29. At one end of the armature shaft of the electric motor 105 is fastened the pulley 110. A third pulley 111 is fastened to the shaft 85 and a driving belt 112 connects the pulleys 110 and 111.

A spur gear 113 is fastened to one end of the armature shaft of the electric motor 105.

Between the extensions 37 and 39 is positioned the receiving roller 114, which has the ends of its shaft 115 journaled in the latter extensions. A spur gear 116 is fastened to the shaft 115 of the roller 114. Rollers 117, 118 and 119 are also positioned between the extensions 37 and 39 and their shafts are journaled thereto. Reduction gears 120, 121 and 122, which are journaled on studs extending from the extension 37 are interposed between the gears 113 and 116.

A warp beam 123 and a pair of squeezing rollers 124 and 125 are positioned between the extensions 36 and 38, and their shafts are journaled thereto. A tank not shown, for drippings may be located below the squeezing rollers 124 and 125. Guide rollers 126 and 127 are also positioned be-

tween the extensions 36 and 38 and their shafts are journaled thereto. A guide roller 128 is positioned in the drying chamber 28 and the ends of its shaft are journaled in the walls 20 and 21.

5 A tank 129 for a sizing fluid is located between and fastened to the extensions 36 and 38. Guide rollers 129a and 129b are journaled to end walls of the tanks 129. The warp of textile 130 operated upon extends from the beam 123, and is led over the roller 127, then over the adjacent roller 129a under the roller 129b and next over the other roller 129a of the tank 129 where it is impregnated with the sizing fluid. The warp then extends over the guide roller 128 and under the guide roller 128 to the outer curved bearing surfaces 54 of the supporting bars 53 of the drum 41.

10 Attention is called to the fact that the portion 130a of the warp 130, between the guide roller 128 and the drum 41 runs in a straight line tangent to said drum 41 for the efficient drying of the warp as it enters the drying chamber 28, before being bent by contacting with the drums in said drying chamber. The warp 130 next contacts with the drums 41, 42, 43, 44, 45, 46 and 47 in a circuitous route through the drying chamber 28.

15 The warp 130 leaves the drying chamber 28 through the opening 35, passes over the guide rollers 117 and 118 and under the roller 119, and is finally wound on the roller 114 as a sized beam of warp.

20 In the heating chamber 27 is indicated a heater 135 with the valve chamber 136. A valve 137 in the chamber 136 extends from a shaft 138. A handle 139 and a pointer 140 extend from the shaft 138. A scale 141 on the wall of the valve chamber 136 is indicated for the pointer 140. A housing 145 with openings 146 extends from the valve chamber 136. A fan not shown is journaled in the housing 145. An electric motor 150 is indicated in the heating chamber 27. The armature shaft of the latter motor is connected to the shaft of the fan in the housing 145. A discharge nozzle 152 extends from the housing 145 and at its ends are indicated the cross-wise discharge outlets 153. A circulating conduit 155 having the supplemental inlet openings 156 leads from the opening 32 in the top wall 22 to the heater 135 on the outside of the drying chamber 28.

25 Referring to Fig. 5 which shows a wiring diagram, the electric motors are again shown at 105 and 150. Wires 160 and 161 connect said electric motors. A source of electric current is shown at 165. Wires 166 and 167 extend from the source of electric current 165. The wire 166 connects the wire 160 and the source of electric current 165. The wire 167 is shown with the terminal 168. A wire 169 extends from the wire 161. An electric switch 170 coacts between the wire 169 and the terminal 168. With the wiring just described both the electric motors 105 and 150 are simultaneously started or stopped by means of the switch 170.

30 To operate the drying apparatus the warp 130 is strung in operative position in a circuitous path about the drums 41 to 47 as indicated in Fig. 1 of the drawing. The switch 170 is closed and thereby both the electric motors 105 and 150 are energized and rotate.

35 With the rotation of the motor 105 the roller 114 turns, whereby the warp 130 moves through

the drying chamber 28 in the circuitous route indicated by the arrows A, to insure a great length of the warp under the influence of the heat in the heating chamber 28. As already called attention to a substantial length of the warp indicated at 130a is heated before becoming curved from contacting with the drums. The warp 130 is drawn from the warp beam 123 and wound on the roller 114. When the warp 130 contacts with the rollers 41 to 47 in the drying chamber 28 it bears on the outer curved bearing surfaces 54 of the bearing bars 53, whereby kinks in the warp are avoided. At the same time the electric motor 105 through the belts 112, 98 and 101 and the belts connecting the pulleys of the shafts 50 rotate the same, and thereby the fans in the drums are turned.

40 The electric motor 150 with its coacting appurtenances turns the fan in the housing 145, whereby air is drawn from the heating chamber 27 and discharged into the drying chamber 28. Simultaneously the air which has contacted with the warp 130 in the drying chamber 28, is drawn therefrom through the conduit 155 and flows through the heater 135 where it is heated. From the heater the air flows through the valve chamber 136, and the amount and velocity of flow of the air is controlled by the valve 137. The air from the heater 135 then flows through the housing 145 and from the latter it is forced through the discharge nozzle 152 and is discharged from the latter through the outlets 153 and enters the drying chamber 28.

45 While the air from the drying chamber is flowing through the circulating conduit 155, fresh air enters the same through its supplemental inlet openings 156. At the same time a portion of the moist air in the drying chamber 28 is drawn therefrom by means of the exhaust fan 90. The air enters the fan 90 through its inlet conduit 91 and is discharged therefrom through its outlet conduit 92. By this means the air in the drying chamber 28 is prevented from being over saturated with moisture. The fan 90 is driven by the electric motor 105, through the interposed belt 45 described therefor.

50 Various modifications may be made in the invention and the present exemplification is to be taken as illustrative and not limitative thereof.

Having described my invention I claim:

55 In a drying apparatus of the character described the combination of a housing comprising a heating chamber and a drying chamber, means in the drying chamber to movably support a warp of textile, means to convey the warp through the drying chamber, a circulating conduit connecting the drying chamber and the heating chamber, a heater in the heating chamber connected to the end of said conduit, a valve chamber extending from the heater, an adjustable valve in said valve chamber, means to indicate the position of the valve in said valve chamber, a housing having openings extending from the valve chamber and positioned in said heating chamber, a fan in the latter housing, an electric motor in the heating chamber to rotate the said fan, a discharge nozzle extending from the housing of the fan into the drying chamber, an exhaust fan for the drying chamber and means to rotate the exhaust fan.
